UNITED STATES PATENT OFFICE.

HARRIE A. BALLARD, OF BOSTON, MASSACHUSETTS, ASSIGNOR TO GENERAL SHOE MACHINERY COMPANY, OF BOSTON, MASSACHUSETTS, A CORPORATION OF MAINE.

SHOE TREE.

Application filed December 22, 1921. Serial No. 524,116.

To all whom it may concern:

Be it known that I, HARRIE A. BALLARD, a citizen of the United States, residing at Boston, in the county of Suffolk and State of Massachusetts, have invented new and useful Improvements in Shoe Trees, of which the following is a specification.

This invention relates to shoe trees and is particularly concerned with the construction by which the effective length of the tree may be adjusted and the construction by which it may be expanded or contracted to operative or inoperative condition with relation to a shoe.

15 For a more complete understanding of this invention reference may be had to the accompanying drawings in which—

Figure 1 is a plan partly broken away of the tree.

20 Figure 2 is a side elevation of the same.

Figure 3 is a view similar to Figure 1 but showing the manner of adjusting the length of the tree.

Figure 4 is a section on line 4—4 of 25 Figure 2.

Referring to the drawings, 1 indicates a toe piece formed substantially in the shape of the forward portion of a last. Extending inwardly from the end of the toe piece is a 30 recess 2 having extending from opposite sides thereof a series of pairs of sockets or openings 3. As shown the recess is at one side of the median line of the toe piece since the length line between the toe and heel of 35 the shoe is nearer the inside of the foot than the outside instead of being symmetrical. Consequently in the arrangement shown the trees are made in rights and lefts. If desired the recess might be placed centrally

40 of the width of the toe piece in which case the same tree might be used for either right or left shoe although separate trees for rights and lefts are preferred. The sockets 3 are designed to receive the outwardly

45 turned forward ends 4 of a pair of spring arms of a bail shaped member 5 which extends rearwardly from the toe piece 1, and at its extreme rear portion passes through an enlarged perforation 6 eccentrically disposed in a heel piece 7, the heel piece by this construction being pivoted on the bail. One end of the heel piece is formed rounded at

50 8 to engage the heel portion of a shoe while its opposite end is formed as a handle 9 by

engagement with which the heel piece may 55 be rocked about its pivotal connection with the bail. The bail and the heel piece are so related as to form a pair of toggle elements which may be straightened or broken by a movement of the handle 9, the straight condition being shown in full lines in Figure 2 and the broken position in dotted lines. When in straight line position the tree is in its operative position for engagement within the toe and heel of the shoe while when the 60 toggle is broken the tree may be removed from the shoe. In this position also a considerable length of the heel piece extends between the arms of member 5 and holds them 65 against the possibility of disengagement 70 from the toe piece.

In order to lock the tree in operative position the heel piece is formed with a widened portion 10 extending from the opening 6 in either direction to form a pair of shoulders 75 engageable with the upper face of the bail when the heel piece is brought slightly beyond its dead center position as shown in Figures 2 and 4.

The tree may be adjusted for different 80 sizes of shoe by springing the sides of the bail inwardly as shown in Figure 3 to remove the ends 4 from the recesses 2, whereupon it may be moved longitudinally with 85 relation to the toe piece to engage with any one of the pairs of sockets 3 which may be desired.

Having thus described an embodiment of the invention it should be evident to those skilled in the art that many changes and 90 modifications might be made therein without departing from its spirit or scope as defined by the appended claims.

I claim:

1. A shoe tree comprising a toe piece, a 95 pair of arms engageable at their forward ends with said toe piece, and a heel piece carried by said arms and movable to prevent disconnection of said arms and toe piece.

2. A shoe tree comprising a toe piece having a recess in its rear end and a series of oppositely disposed sockets opening into said recess, a heel piece, and means for connecting said toe and heel pieces comprising spring arms pivoted to said heel piece and having outwardly turned ends fitting interchangeably in any pair of oppositely disposed sockets in said toe piece, said heel piece being movable to engage between said 100 105

arms toward said toe piece and prevent detachment of said arms therefrom.

3. A shoe tree comprising a toe piece having a series of opposed pairs of outwardly extending sockets, a bail shaped member having its free ends outwardly turned to engage in any of said pairs of sockets, and a heel piece pivoted on said member and movable thereon to expand and contract said tree, the heel piece when in tree-expanded position projecting between the sides of said member sufficiently to prevent disengagement of said ends from said sockets.

4. A shoe tree comprising a toe piece having a series of opposed pairs of outwardly extending sockets, a bail shaped member having its free ends outwardly turned to engage in any of said pairs of sockets, and a heel piece pivoted on said member and movable thereon to expand and contract

said tree, the heel piece when in tree-expanded position projecting between the sides of said member sufficiently to prevent disengagement of said ends from said sockets, and said heel piece having a portion 25 acting with said member as a toggle lock to retain it in tree-expanded position.

5. A shoe tree having a toe piece, a bail shaped member extending rearwardly from said toe piece, a heel piece pivoted on said member and forming a toggle therewith which is straightened when the tree is expanded, and a shoulder on said heel piece engageable with said member when the tree is expanded and serving as a lock for said 30 35 toggle.

In testimony whereof I have affixed my signature.

HARRIE A. BALLARD.
